CLAIM

The ornamental design for a double baffle tile for furnace for oil refineries, as shown.

DESCRIPTION

FIG. 1 is a front and left side perspective view of a double baffle tile for furnace for oil refineries, showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof; and

FIG. 7 is a right side elevation view thereof.

FIG-2

チユロ-3-チユロ-4-チユロ-5-チユロ-6-チユロ-7-UNITED STATES PATENT OFFICE
CERTIFICATE OF CORRECTION

Patent No. Des. 318,527 Dated July 23, 1991

Inventor(s) Frank L. Groenewold, et al

It is certified that error appears in the above-identified patent and that said Letters Patent is hereby corrected as shown below:

Col.   Line

- 2   -   "Fig. 3 is a rear elevation view" should read
            --Fig. 3 is a back view--
- 2   -   "Fig. 4 is a top plan view" should read
            --Fig. 4 is a rear elevation view--

Signed and Sealed this
Ninth Day of March, 1993

Attest:

STEPHEN G. KUNIN

Attesting Officer

Acting Commissioner of Patents and Trademarks
